UNITED STATES PATENT OFFICE.

SIMON E. SCHROEDER AND CHARLES W. BIRD, OF MINIER, ILLINOIS.

DRIVING MECHANISM FOR OPERATING DEVICES.

1,288,694.

Specification of Letters Patent. Patented Dec. 24, 1918.

Application filed August 19, 1914. Serial No. 857,613.

To all whom it may concern:

Be it known that we, SIMON E. SCHROEDER and CHARLES W. BIRD, citizens of the United States, residing at Minier, in the county of 5 Tazewell and State of Illinois, have invented certain new and useful Improvements in Driving Mechanism for Operating Devices, of which the following is a specification.

Our invention relates to driving mechanism for operating devices and support therefor.

Our invention has particular application to combined washing and wringing devices, but as here presented has special relation to 15 the positioning of the wringer relative to containers used in connection with doing of a family washing.

Our invention consists of driving parts applied to operate a wringer mechanism inter-changeably in different locations relative to 20 containers in different positions upon a supporting frame. Said driving connections being associated with independent wringer supports, but having a common driving 25 means.

The invention also comprehends connections such that the wringer in its different placements may be driven in reverse directions under the control of the operator, or 30 may be rendered inoperative by a certain manipulation of operating parts.

Our invention embraces organized parts effective for carrying out complete washing functions, and to details more or less im- 35 portant which will be referred to in connection with the technical description following:

Referring to drawings,

Figure 1 is a plan view of the washing 40 machine showing our improvements applied;

Fig. 2 is a side elevation of the same;

Fig. 3 is an end view with parts broken away to show detailed parts;

Fig. 4 is an opposite end view from that 45 shown in Fig. 3, with parts broken away to show detailed connections and parts;

Fig. 5 is a longitudinal sectional view on the line $x-x$ of Fig. 1, however omitting 50 certain structural parts above the platform support;

Fig. 6 is a detailed view in part of a wringer and driven member, the supporting member parts being sectioned to show the

manner of connecting the wringer to the driven member;

Fig. 7 is a transverse sectional view on the line $y-y$ of Fig. 1, certain structural parts above and below the platform being omitted; and

Fig. 8 is a detailed sectional view showing 60 connections for effecting the driving of the wringer and the reversal of the movement thereof.

Our knowledge of the art relating to the subject to which this invention is directed 65 advises us that it is common in the patent and in the practical art to associate a wringer in close connection with an agitator tub for convenience of work, and also to establish a common driving connection for both 70 driven elements; also that reversing means for the wringer elements are old; and likewise it is old to associate the wringer with the agitator receptacle and a main support in such a manner that the wringer may be 75 moved in different positions relative to said support and agitator receptacle.

Types of machines of the class above noted are exemplified in structures where a wringer is mounted upon the agitator tub, and a common driving connection is provided for both the agitator tub and the wringer, and including a reversing arrangement for the latter; and similar machines, with the wringer supported in a manner to permit it to be 80 swung around horizontally from a pivoted support. Machines of what is known as the "platform type," wherein the wringer is moved lengthwise upon a frame support for the working parts of the machine, including 85 common driving connections for the agitator devices and the wringer, means for reversing the wringer and means for operating the wringer at determined spaced positions, and those in which the wringer is slidable upon 90 a square driving shaft and may be driven in any position of placement; and also we have knowledge of machines comprehending the association of the agitating means and tub and the wringer under similar driving connections and relations as above noted, that distinguish it from the others in that the wringer supporting frame is mounted across 95 the machine and pivoted in a manner to permit the frame and the wringer support thereon to be swung from the tub to a definite 100 105

position of placement, and back again, at the will of the operator, and this without interfering with, or necessitating either breaking or establishing a different driving connection.

It is with the view of improving upon these several types of washing machines that we have developed our present structure.

Referring to the drawings:

- 10 2 refers generally to a frame support, commonly called a "platform";
 15 3 is a tub designed to contain the clothing to be washed, and within the tub there is designed to be placed a dolly (not shown).
 20 This dolly is designed to be operated through driving connections from the power shaft 4, but as these connected working parts do not constitute any part of our present invention, they are not herein pointed out particularly.

Two wringer supports are provided, which are suitably spaced apart to meet the functions and theory of use comprehended herein. Support 4^a is mounted directly upon, 25 and at one side of the tub, but in such position as to in no way interfere with the raising of the lid of the latter; the other support comprises uprights 5, and spaced the width of the machine frame across the top supporting cross frame piece 6.

Open seats or brackets as 7 and 8 are provided respectively for wringer supporting parts 6 and 4^a.

The wringer is designed to be removably associated with both supports named, and to be driven in its different positions. The driven connection for the wringer in its different positions comprises the drive shaft 4, adapted to be driven in a continuous direction from a belt pulley as 9, suitably connected with power, or from an electric motor directly associated with the frame support; the counter-shaft 10 extending longitudinally on the platform connected to be driven from shaft 4 by means of spur gears 11 and 12 respectively, fixed upon shafts 4 and 10; shaft 13 in axial alinement with shaft 10, and the ends of each being substantially in contact; vertical shafts 14 and 15 extending respectively to the supports 4^a and 6, and each provided with collars as "a" fixed at the upper ends thereof, said collar being squared interiorly and protruding through openings in said supports, and supported in such relation therewith as to adapt them for connection with the wringer or a connecting part thereof; gear parts for effecting the driving and reversing of shafts 14 and 15, comprising bevel gear 16 normally loose on shaft 10, bevel gear 17 fixed on shaft 14, bevel gear 18 fixed on shaft 13, bevel gear 19 fixed on shaft 13, and bevel gear 20 fixed on shaft 15.

The particular mechanism for accomplishing the driving of shafts 14 and 15, and for

reversing the movement of said shafts, consists of the shiftable clutch collar 21 splined on shaft 10 and provided with clutch faces as 22 on each side, and facing in the same direction, and similar clutch faces 23 integral with, or forming a part of, the hubs respectively of bevel gears 16 and 18.

A housing, or gear box, 24 is provided as disclosed.

The particular driving connections for the wringer that are designed to be directly associated with and supported thereby comprise bevel gear 25 fixed directly to one of the wringer roll shafts; bevel gear 26 fixed upon a shaft supported in the bracket 27, the latter secured to the wringer frame, the lower end of said shaft being shown in Fig. 6 at 28, said portion of said shaft fitting in either of collars "a" to establish a driving connection therebetween.

The wringer is applied for driving connections with either of shafts 14 and 15 by simply inserting the squared portions of 28 of the wringer shaft within either of collars "a", the flanged portion "b" of the sleeve 90 portion of bracket 27 serving as a stop in its rest upon the upper edge of either of said collars "a". In placing the wringer in position for operation with either shaft 14 or 15, the other end of the wringer, from 95 that whereby the driving connection is established, is seated in brackets 7 and 8, and thus the wringer is held for operation.

Clutch collar 21 is shifted from either of levers 29 or 30, said levers respectively 100 being pivoted at 31 and 32, and their lower ends pivotally connected by reach, or bar, 33. The connected levers described have connection with clutch collar 21 through lever 34, the latter fulcrumed, or pivoted, as 105 at 35 to a part connected with the framework, its outer end passing through an opening in lever 31, and similarly an eye in the end of reach 33. The parts are secured in position shown by means of a cotter pin, or 110 other suitable means. The other end of lever 34 is furcated as at 36 and engages groove 37 in clutch collar 21.

The operation of the device is as follows: The wringer having been placed in operative connection with shaft 14, and assuming that belt wheel 9 is driven in the direction of the arrow, and that clutch collar 21 has been thrown into engagement with gear wheel 16, shaft 14 will be driven in one 120 direction. Then, if clutch collar 21 be shifted to engage gear 18, shaft 14 will be driven in the reverse direction. The adjustment of the collar is accomplished by the operator through lever 29 in this position of the wringer, see Fig. 2, and through the operation or manipulation of said lever clutch may be thrown to either of the engagements above specified, to effect either of the arrangements above specified, or it 130

may be thrown into a neutral position, at which time the wringer will be at rest.

Shaft 15 is driven through the same connections that drive shaft 14, so that when 5 the wringer is operatively connected with said shaft it will be driven in either direction desired through the manipulation of the operator, preferably of lever 30, and it may in the same manner be thrown to a neutral 10 position. Both shafts 14 and 15 are driven at the same time under all conditions. However, their relative direction of simultaneous drive may be different, depending upon the 15 positioning of bevel gears 19 and 20; that is, if said gears 19 and 20 are placed in the relation shown in the drawings, then the shafts, under all conditions of operation, will turn 20 relatively in opposite directions; whereas, if shaft 13 be extended and gear 19 be placed on the opposite side of gear 20, the shafts are run relatively in the same direction. This matter is for the choice of the builder.

In either of the connections as above specified, that is with shafts 14 and 15, there is 25 no different operation of the driving parts directly connected with the wringer, and hence no detailed description of the operation of these parts in the two different positions need be entered into.

30 Our experience in the course of an extended manufacture of washing machines has taught us that any required movement of the wringer support, whether it be on a sliding frame, a frame swingable about a 35 vertical pivot, or about a horizontal pivot, is objectionable, in that the movable parts in time lose their rigidity; that is, they become loosened and shaky, which leads, of course, to repair and readjustment, and likewise the 40 wringer and gear supporting parts from the normal relation to their gear connections out of normal mesh, and hence causes wear and the expenditure of additional power over the normal, and generally disqualifies the 45 machine for the highest grade of efficiency. We seek by our invention by and through the fixed and immovable supports for the wringer to avoid these disadvantages. It is a very small matter to simply lift the 50 wringer from one position to the other, and generally is a more convenient method of changing its position, as compared with the plan followed out in the several types of machines heretofore specified.

55 We have herein exemplified in the drawings and specifications one form of embodiment of our invention, however, we are looking to the principle rather than to form, and deem ourselves at liberty to claim 60 all forms in which our invention may be embodied that is in effect and equivalency the same as we herein disclose.

What we claim is:

1. In a mechanism driving device, a sup- 65 port, an operating mechanism, a plurality

of driving connections in permanent spaced relation upon the support adapted interchangeably to drive said mechanism, and means for operating said driving connections to drive the operating mechanism in either of its operative connections in reversed directions.

2. In a mechanism operative device, a support, an operating mechanism, a plurality of members spaced apart and fixed in permanent positions relative to the support adapted for connection interchangeably to drive the operating mechanism, and means for operating said mechanism driving members in different positions of placement in 75 reversed directions or to disconnect said operating mechanism to allow it to be at rest.

3. In a mechanism driving device, a support, an operating mechanism, plural members for interchangeably driving said operating mechanism spaced apart upon the support in permanent positions, devices upon the operating mechanism detachably connectible with said plural driving members, and means for operating said driving members in 85 different positions of placement in reversed directions or to disconnect said operating mechanism to allow it to be at rest.

4. In a mechanism driving device, a support, an operating mechanism, a plurality of 95 plural members for interchangeably driving the operating device, spaced apart and each being fixed as to position with relation to the support, and means for driving the mechanism operating members alternating in reverse directions in different positions of placement in reversed directions or to disconnect said operating mechanism to allow it to be at rest.

5. In a mechanism driving device, a support, an operating mechanism, a plurality of shafts for interchangeably driving the single operating mechanism, the same being spaced apart and having permanent position with relation to the support, a member upon the 100 operating mechanism adapted for detachable driving connection with said shafts, and means for operating said mechanism driving shafts alternating in reverse directions.

6. In a mechanism driving device, a support, an operating mechanism, an operating device, plural members permanently fixed upon the support in spaced relation adapted for driving connection with the operating mechanism, a drive shaft having a constant direction of movement, a reversible shaft driven therefrom and having a driving connection with one of said operative mechanism driving members, and means connecting the drive and reversible shafts with the other of said operating mechanism driving members for effecting an alternate reversal of movement of said operating mechanism driving member, and also a corresponding reversal of the direction of movement of the 115 120 125 130

other of said operating mechanism driving members.

7. In a mechanism driving device, a support, an operating mechanism, a plurality of members for interchangeably driving the single operating device, spaced apart, and each having a fixed position with relation to the support, a member upon the operating mechanism adaptable for detachable driving connection with said plural driving members, and means for operating the plural mechanism driving members each in an alternating reverse direction, comprising a drive shaft operable in a constant direction, a shaft reversibly driven therefrom, gear connection between the reversibly driven shaft and one of the operating mechanism driving members, and gear connections on the other of said mechanism operating members, and means for operating the plural reversibly driven shafts.

8. In a mechanism driving device, a support, an operating mechanism, a plurality of members for interchangeably driving the single operating device, spaced apart, and each having a fixed position with relation to the support, a member upon the operating mechanism adaptable for detachable driving connection with said plural driving members, and means for operating the plural mechanism driving members each in an alternating reverse direction, comprising a drive shaft operable in a constant direction, a shaft reversibly driven therefrom, gear connection between the reversibly driven shaft and one of the operating mechanism driving members, gear connections on the other of said mechanism operating members operable, both from the drive and reversibly driven shafts, and means to effect reversal of the movement of said driven reversible shaft and the plural driving members for the operating mechanism.

9. In a mechanism driving device, a support, an operating mechanism, a plurality of members for interchangeably driving the single operating device, spaced apart, and each having a fixed position with relation to the support, a member upon the operating mechanism adaptable for detachable driving connection with said plural driving members, and means for operating the plural mechanism driving members each in an alternating reverse direction, comprising a drive shaft operable in a constant direction, a shaft reversibly driven therefrom, gear connection between the reversibly driven shaft and one of the operating mechanism driving members, gear connections on the other of said mechanism operating members operable, both from the drive and reversibly driven shafts, means to effect reversal of the movement of said driven reversible shaft

and the plural driving members for the operating mechanism, and means for wholly disconnecting the reversible and plural member driving connections for the operating mechanism from the drive shaft whereby the former may be at rest.

10. In a device of the class described, in combination, a support, a vertical drive shaft in said support, provided with a seating member at its upper end formed for clutch engagement with an opposing member adapted to be positioned relative thereto at varying angles about the axes thereof; an operating mechanism including a horizontally disposed shaft provided with a gear thereon; a vertically disposed short shaft alinable with the vertical drive shaft provided with a gear at its upper end adapted to engage the horizontal shaft of the operating mechanism, and fashioned for detachable engagement with the clutch member of the drive shaft at various angles of placement about the axis of said drive shaft, and manually removable therefrom, and a sleeve member suitably connected to the operating mechanism and supporting said short shaft and fashioned for seating upon the seating member of the drive shaft, whereby the operating mechanism may be lifted from its connection with the drive shaft and positioned at various angles about the axis of the latter without the removal of parts or attaching means.

11. In a device of the class described, in combination, a vertical drive shaft, a combined seating and clutch member, at its upper end fashioned to seat and engage opposing members of an operating mechanism at various angles about the axis of the drive shaft, an operating mechanism including a horizontal shaft provided with a gear thereon, and means on the operating mechanism centered with respect to the drive shaft and seating member thereon, and adapted for detachable seating, and to establish driving connection between the seat and clutch members of the drive shaft and the gear of the horizontal shaft of the operating mechanism, but in a relation that will permit the operating mechanism to be lifted bodily from the seat and driving connection on the horizontal shaft and to be placed at varying angular positions about the axis of said driving shaft to establish driving connection at such varying angles thereabout.

In testimony whereof we affix our signatures in presence of two witnesses.
